METHOD AND MEANS FOR CUTTING WEBS

Adolph M. Zuckerman, New York, N. Y., assignor
to R. Hoe & Co., Inc., New York, N. Y., a corpora-
tion of New York; Irving Trust Company,
permanent trustee

Application April 20, 1932, Serial No. 606,386

3 Claims. (Cl. 164—68)

This invention relates to improvements in web cutting and is particularly applicable to cutting or severing a running web or webs of paper or other material as it passes from a printing or other machine to a folder, assembly means or otherwise as desired.

It is one of the objects of this invention to neatly sever a continuous and moving web, into a plurality of sheets of predetermined lengths, the 10 cut edges of which are perpendicular to the side margins thereof or otherwise as desired.

In prior operations of this character it has been customary to propel the web at a desired speed and to cut it at intervals into sheets of substantially uniform lengths by a pair of rotating knives acting successively in timed relation therewith.

Such knives have been operated at peripheral speeds substantially equal to the speed of translation of the running web but it has been found, 20 that in an operation so conducted, the cut edges of some of the sheets, frequently adhere to the knives, due to static electricity, or for other causes, with the result of deflecting such sheets from the proper path, and preventing their entrance into the guides which should conduct them further. Due also to the deflection of the web so caused, it is sometimes torn, crumpled or distorted, frequently causing chokes, with consequent damage to the machinery, all of which is undesirable.

It is one of the objects of this invention to positively and accurately cut a running web into sheets of desired lengths while obviating the difficulties previously mentioned, and this is accomplished by rotating the cutting knives at peripheral speeds slightly greater than the speed of translation of the web keeping them however, in timed relation therewith.

By arranging the operation and mechanism in 40 this way, the cutting knives, after severing the web, move away from its ends by reason of the fact that their speed is greater than that of the web, and the latter is consequently not deflected nor crumpled so that it is delivered accurately to the guides or other apparatus adapted to next and successively receive the cut sheets.

It is also an object of this invention to provide a method and means for cutting a running web into sheets, which are simple and efficient, while 50 the mechanism is durable and inexpensive and at

the same time, it is convenient, practical and serviceable in use.

With the foregoing and other objects in view, which will appear as the description proceeds, the invention resides in the method of operation and 5 the combination and arrangement of mechanism therefor, and the details thereof, all as herein described and claimed, it being understood that various changes in the precise embodiments of the invention hereby disclosed may be made 10 within the scope of what is claimed without departing from the spirit of the invention.

The preferred embodiment of the mechanism of the invention is illustrated in the accompanying drawing, wherein:—

Figure 1 is an elevation of a machine embodying this invention looking at the ends of the cutting cylinders in the general direction of their axes;

Figure 2 is a detailed end view of the pair of 20 cutting cylinders showing their knives or cutters in opposed positions when severing the web; and

Figure 3 is an end view of the pair of cutting cylinders showing the knives slightly advanced 25 and in the positions occupied shortly after severing the web.

Referring now to the characters of reference on the drawing:—

The frame of the machine is indicated as 11 on which the cutting cylinders 12 and 16 are 30 rotatably mounted in bearings as shown and are geared together to insure that the shear knives 14 and 18 carried thereby shall register as indicated in Figure 2.

One of the cutting cylinders is indicated as 12, 35 secured on the rotatable shaft 13 and provided with the knife or cutter 14 mounted on its holder 15 and adjustably secured thereon by the tap bolts and adjusting screw as illustrated.

The companion cutting cylinder 16 is mounted 40 on the rotatable shaft 17 and is geared to its mate 12 so that it rotates in harmony therewith to insure the registry of their respective knives or cutters 14 and 18. This cutting cylinder 16 has a similar knife 18 mounted on its holder 19 to 45 which it is also adjustably secured as shown. The cylinders 12 and 16 are arranged or adjusted so that their adjacent peripheries do not operably engage the web with sufficient pressure to feed it, but only serve to additionally guide the web. 50

On the delivery side of the cutting cylinders 12 and 16 and adjacent thereto are the guides 20, adapted to receive the sheets W' which have been cut from the running web W by the co-operative shearing effect of the rotating knives 14 and 18.

As shown at the upper left hand side of Figure 1, a compensating roller 21 is rotatably mounted on the rocker arms, one of which is shown and indicated as 22, which are capable of adjustable movement around the axis of the rock shaft 23 by the movement of the crank 24 which is provided with an operating rod 25 having means for adjusting and securing it in position, not shown.

After the running web W has passed over the roller 21, it is gripped and propelled by the driven feed roller 26 and between it and the propeller disks 27. These propeller disks are preferably a plurality of short rollers rotatably mounted and capable of being forced against the web and toward the roller 26 by swinging the rocker arms 28 about their rock shaft 29 by the crank 30 which may be adjusted and secured in position by any customary means adapted to maintain the desired pressure.

The apparatus is driven from the main shaft 31 which may be rotated by any suitable source of power. This rotates the bevel gear 32 which 30 rotates the bevel gear 33 and the spur gear 34 mounted on the same shaft as the cylinder 35, which latter is geared to and rotates the cylinder 36. These cylinders 35 and 36 may be forwarding cylinders, folding cylinders, collecting cylinders or any type desired to receive and dispose of the cut sheets in various manners dependent on the product desired.

The spur gear 34, drives an idler gear 37 which meshes with the gear 38 to drive the cutting cylinder 16, and this cutting cylinder is geared to its companion cylinder 12, and these therefore rotate in harmony and to insure the registry of their respective cutting knives 18 and 14. The gear 37 also meshes with the gear 39 which in turn meshes with the gear 40 which drives the feed rolls 26 through the gear mounted on their shaft.

Between the feed and propeller rollers 26 and 27 and the cutting cylinders 12 and 16, guides 41 are supported on the shafts 42 and are adapted to direct the web W into the bite of the cutting cylinders.

As indicated in Figure 1, another pair of nipping rollers is provided comprising the roller 43 driven by the gear 39 at greater peripheral speed than the feed roller 26 and its companion propeller rollers or disks 44 which are adapted to press against the sheets W' and forcibly contact them with these rollers to insure their forward movement. The rollers 44 are rotatably mounted near the ends of rocker arms 45 which are adapted to be swung by the rock shaft 46 toward the roller 43 and secured in position by means not shown, but such as customary for this use. The rollers 43 and 44 project between the guides 20 in order to contact with the cut sheets W' and are adapted to forward them to the succeeding mechanism or to their destination.

In order to make a straight cut, the knives 14 and 18 are arranged on their respective cutting cylinders in directions slightly inclined to the cylinder axes, or helically with respect to the surfaces of the cylinders. As these knives revolve they are adapted to meet in registry and thus shear the web, as indicated in Figure 2 of

the drawing, in which the cut is about accomplished by the rotation of the cutting cylinders in the directions of the arrows.

In order to simplify the drawing, and for the sake of its clarity, the various gears and cylinders are indicated in Figure 1 by simple circles composed of full lines where directly visible and by broken lines where behind other features in this view, and their directions of rotation are indicated by the various arrows.

The sizes of the cutting cylinders and the gear ratios of the various drives is such that the peripheral speed of revolution of the knives 14 and 18 is slightly greater than the speed of the running web. The knives therefore depart quickly 15 from the cut ends of the web and thus avoid deflecting, crumpling or distorting it. The effect of this is to insure that the leading end of the web is positively and neatly entered between the guide bars 20, thus obviating the difficulties dis- 20 closed herein.

This arrangement and the means whereby this is accomplished form valuable and important features of this invention.

As the mechanism of this invention is equally 25 adapted to operate upon one web or a plurality of associated webs, it should be understood that the words web or webs may be used interchangeably herein.

What I claim is:

1. The method of cutting a printed web, which consists in propelling the web at a given speed and in predetermined registered relation, constantly revolving two cooperating and mutually registrable cutting edges at a speed slightly 35 greater than the speed of the propelled web and in register with the printed matter on the web to thereby sever the web into separate sheets bearing predetermined printed matter, guiding the sheets away from the cutting edges from a 40 point immediately adjacent the cutting point of the cutting edges, and propelling the sheets away from the cutting edges at a speed greater than the speed of the propelled web.

2. In a web cutting mechanism for a printing 45 machine, means for feeding the printed web at a given speed, a compensating member in advance of the feeding means to supply the printed web to the feeding means with the printed matter on the web in predetermined registered relation, a pair of rotary carriers cooperating to engage and guide the printed web without exerting a feeding pressure thereon, means for guiding the feeding web from the web feeding means to the rotary carriers, a pair of coacting cutting 50 knives, one knife operably supported by each carrier, the carriers and cutting knives being rotated constantly at a speed slightly greater than the speed of the web feeding means and in register with the printed matter on the feeding web 60 to cut the web into sheets of predetermined length, guides leading from the carriers and constructed and arranged to guide the sheets cut from the web away from the cutting knives, and means for propelling the sheets along the 65 guides away from the knives at a speed slightly greater than the speed of the feeding web.

3. In a web cutting mechanism for a printing 70 machine, means for feeding the printed web at a given speed, an adjustable compensating member in advance of the feeding means to supply the printed web to the feeding means with the printed matter on the web in predetermined registered relation, a pair of rotary carriers co-operating to engage and guide the web without 75

exerting feeding pressure thereon, means for guiding the feeding web from the feeding means to the rotary carriers, a pair of coacting cutting knives, one knife operably supported on each carrier, the carriers and cutting knives being constantly rotated at a speed slightly greater than the speed of the web feeding means and in register with the printed matter on the feeding web to cut the web into sheets of predetermined length having predetermined printed matter

thereon, web guides leading from the carriers and having laterally enlarged entrance terminals positioned immediately adjacent the carriers and constructed and arranged to guide the sheets cut from the web away from the knives, and means for propelling the sheets away from the knives along the guides at a speed slightly greater than the speed of the feeding web. 5

ADOLPH M. ZUCKERMAN. 10
